WEB HOLDING AND GUIDING STOPPER

George Frederick French, Manchester, England,
assignor to Thomas French & Sons Limited,
Manchester, England, a corporation of Great
Britain

Original application May 19, 1937, Serial No.
143,556. Divided and this application Decem-
ber 29, 1937, Serial No. 182,181. In Great Brit-
ain July 27, 1935

6 Claims. (Cl. 139—291)

This invention refers to webbing composed of two band-like lengths of woven material joined at intervals by cross tapes. One example of such webbing is that used in Venetian blinds, and another example is that called "pocket" tape, and used inside helmets for holding strips of cork or pith.

The present application is a division of my co-pending application, Serial No. 143,556, filed May 19, 1937. This application is closely related to my co-pending application Ser. No. 67,809, filed March 9, 1936.

In the weaving of ladder or like webbing, the webbing passes through a device called a "stopper" which serves to support and guide the webbing as it passes forward to the breast beam and to its take-up and delivery rollers at the front of the loom and into the work box.

The previously known "stopper" consists of a stout metal rod bent at right angles to its length at one end to form an open-ended U-shaped loop, through which the webbing passes, and at another part fixed to the breast beam of the loom. Such known stopper has several drawbacks, but mainly that it allows the webs to work out through the open side of the loop, thus causing bad weaving, as well as allowing the webs to project beyond the width of the cloth in the loom batten, such drawbacks also causing long stoppages of the loom to correct the weave. A further drawback is that the loop part of the stopper does not hold the webs close together, especially at the time and point of the beat up, which results in slack weaving and, in the case of ladder and like webbing, results in the aforesaid excessive portions of the warp threads of the cross tapes being left unwoven, and necessitating the subsequent cutting away or trimming by hand of the surplus warp threads when separating the outer bandings from each other. A further fault of the known "stopper" is that it is only supported at one side, and its opposite side is free to move and get out of line with the loom batten. It is also incapable of yielding bodily if and when struck by the loom batten.

A further object of this invention is a construction of "stopper" and stopper-supporting means by which the foregoing drawbacks are eliminated.

In the accompanying drawing, constituting a part hereof and in which like reference characters indicate like parts,

Fig. 1 is a plan view showing a portion of the breast beam of a loom for making ladder webbing, with the stopper of the present invention in place thereon;

Fig. 2 is a cross-sectional view thereof taken along the line 2—2 of Fig. 1;

Fig. 3 is a perspective view of the stopper shown in Figs. 1 and 2 removed from the loom;

Fig. 4 is a view similar to Fig. 3 of a modified form of stopper showing a diagonally placed slot in one of the faces thereof;

Fig. 5 is a plan view similar to Fig. 1, showing a resilient mounting for the rods which support the stopper; and

Fig. 6 is a fragmentary plan view of the stopper, showing a modified form of supporting rod.

As indicated in Fig. 1, there is shown the beam 1, constituting a part of the breast of the loom, and rods 2 and 3 threaded through openings 4, 15 and 5 respectively, and held in place by nuts 6. The rods 2 and 3 extend forward a substantial distance and then are curved inwardly at 7 and 8 respectively, terminating in reduced, small ends 9 and 10 respectively. The stopper 11, as best shown in Fig. 3, has an upper and lower flat face 12 and 13, with the sides 14 and 15 closed and having a narrow slot or opening 16 extending therethrough. On each of the sides of said slot is an opening 17, slightly larger in diameter than the ends 9 and 10 of rods 2 and 3 for the reception of said rods to be held loosely in place. The several sets of threads 18, 19, 20 and 21 converge from the loom itself and approach the slot 16 of the stopper 11 and the weaving of the webbing takes place immediately in front of said slot. By reason of the divergence of threads 18, 19, 20 and 21, and the fact that they are under tension in the loom, there is a component of force tending to press the stopper 11 in the direction of the breast beam of the loom, thereby holding it positively in place on the rods 2 and 3. The woven ladder webbing 22 passes out of the loom in the direction of the arrow 23.

A modification of the stopper is shown in Fig. 4, wherein the upper surface 12 is provided with a diagonally placed slot 24, providing an opening whereby the woven webbing 22 may be removed from slot 16 without disturbing the alignment of the parts.

In Fig. 5 a different type of mounting is shown, wherein the rods 2 and 3, instead of being rigidly mounted as shown in Fig. 1, have their ends 4 and 5 passing through the breast beam 1 and being held from displacement by nuts 25 and 26. On the opposite end of said breast 1 and surrounding each of the rods 2 and 3 is a spring 27 held in place by a pin or other means 28. This provides a resilient mounting, but one which in the

absence of sudden blows assumes its normal and natural position.

It has been found that sometimes accidentally one of the rods 2 or 3 may become somewhat bent and, therefore, the stopper 11 may assume a position slightly out of line, making it difficult for the shuttles to weave between threads 18, 19, 20 and 21, and in some instances, causing the shuttles to strike some of said threads, all of which might 10 tend to produce defective weaving. In order to overcome this possible disadvantage, a still further modified form of supporting means for the stopper has been provided. In this case, instead of two rods 2 and 3, there is provided but a single 15 rod 29 (Fig. 6), one end of which is attached to the breast beam of the machine in any desired manner, and the other end of which is bent inwardly at 30 with the extremity or tip 31 of the rod 29 touching the approximate center of the stopper 11 at a point either below or above the woven band 22. There need be no additional contact between the rod 29 and the stopper 11. In 20 operation, because of the tension of the diverging threads 18, 19, 20 and 21, there is a force 25 tending to push the stopper against the tip 31 of the rod 29 and to hold it in place. In addition, if by reason of an accidental blow or otherwise, there is a tipping of the stopper 11, it will immediately come back freely to its normal position, 30 and thereby there will be avoided any interference between the shuttles and the warp threads.

The two webs, as they are woven, pass through the "stopper" from the heald side, and thence over the breast piece to the take-up and delivery 35 rollers and work box.

With the stopper fitted to and held by the rod or rods in a position such that its forward longitudinal side lies near to the "fells" of the webs and with the slot comparatively narrow and its 40 upper and lower sides flat and parallel, it holds the two webs firmly and closely together during each beat-up of the weft, which results in tighter weaving, and it cooperates with the healds in reducing the "dwell" and giving a longer binding-in of the cross tapes.

To permit of the webs being removed from the stopper without disturbing their connection with the take-up roller, say when requiring to inspect the inside or underside of the webs, the upper 45 thickness of the stopper may, as shown in Fig. 4, be formed with an opening, preferably diagonal, through which the webs may be withdrawn, and through which they may be passed back again into the stopper after inspection. Alternatively, the stopper may be removed bodily from the rods 50 and slid along the webs. The opening in the stopper also allows of the stopper being used to anchor the loose weft after reshuttling and the broken warp ends after being drawn in.

To afford a yielding contact of the stopper if and when struck by the loom batten, the rods 55 may be fitted with coiled springs, see Fig. 5, which yield on the stopper being struck by the batten, but otherwise hold it in its normal forward position.

By reason of the slot in the stopper being closed

at the ends next the sides of the stopper, the webs cannot leave the stopper sideways, as in the known stopper.

Lastly, it will be seen that by reason of the tighter weaving of the webbing due to the altered heald motions, the increase in the length of each binding in, the reduction in length of the loose warps and weft between the binding in, and the firmer hold on the webbing at the "fells", a much firmer and stronger construction of webbing is 10 obtained.

What I claim is:

1. In a loom for weaving webbing, a web holding and guiding stopper comprising a member having therein a narrow, flat channel closed on 15 all faces, through which said web is adapted to pass and a diagonal slot in said stopper to allow the removal of said web.

2. In a loom for weaving webbing, a web holding and guiding stopper comprising a member having therein a narrow, flat channel closed on all faces, through which said web is adapted to pass and means for resiliently attaching the said stopper to said loom to allow yielding thereof, the direction of said yielding being the direction of 25 travel of the web being woven.

3. In a loom for weaving webbing, a web holding and guiding stopper comprising a member having therein a narrow, flat channel closed on 30 all faces, through which said web is adapted to pass and a slot in one of the faces of said stopper to allow removal of said web.

4. In a loom for weaving webbing, a web holding and guiding stopper comprising a member having therein a narrow, flat channel closed at 35 the sides, through which said web is adapted to pass, rods extending into the respective sides of said stopper, the opposite ends of said rods being secured in the breast beam of said loom, said stopper being detachably secured to said rods 40 and being removable therefrom by shifting said stopper.

5. In a loom for weaving webbing, a web holding and guiding stopper comprising a member having therein a narrow flat channel closed at 45 the sides, through which said web is adapted to pass, a support secured to the breast beam of said loom and extending to said stopper, said support contacting with but unattached to said stopper on the side thereof opposite the threads 50 being woven, said stopper being held in said contact by the pressure of the converging threads being woven.

6. In a loom for weaving webbing, a web holding and guiding stopper comprising a member having therein a narrow flat channel closed at the sides, through which said web is adapted to pass, a support secured to the breast beam of said loom and extending to said stopper, said support contacting with said stopper at a point below said 60 web but unattached to said stopper on the side thereof opposite the threads being woven, said stopper being held in said contact by the pressure of the converging threads being woven.
